TARGET PASTING DEVICE

William E. Hummel, Santa Barbara, Calif.

Application January 8, 1935, Serial No. 908

1 Claim. (Cl. 91—14.5)

This invention relates to a target pasting device.

In target practice the perforations made by projectiles passing through the target are usually sealed over by means of tape formed of paper and the devices ordinarily employed are rather cumbersome and therefore are of such a size that it is inconvenient to carry them around. Two tapes, black and white, are ordinarily employed for the purpose and it frequently happens that separate devices are employed for each kind of tape.

It is an object of the present invention to provide a compact device of convenient size which may be carried in the pocket of the person who attends to the closing of the openings in the target, the device being so constructed that it may be held in one hand of the operator while the other hand may be employed for drawing the glued tape over the moistener and for tearing off predetermined lengths of the tape.

Another object of the invention is the provision of a device which will house one or more rolls of glued tape with the housing being provided with an offset portion forming a chamber for a moistener, the chamber being provided with an open end through which the moistener projects and the open end is disposed in such a manner that said end will be in substantially a plane tangent to the circular wall of the housing.

A further object of the invention is the provision of a pasting device including a housing for rolls of glued tape with the housing having an offset chamber for a moistener, said housing having an outlet and a curved guide for the tape, one wall of the guide forming one wall of the chamber, a cover being provided for the open end of the chamber and adapted to act as a support for the tape when in open position and when the tape is being drawn over the moistener which projects through the open end of the chamber.

This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claims.

In the drawing:

Figure 1 is a view in perspective of the pasting device constructed in accordance with the principles of my invention.

Figure 2 is a vertical section taken along the line 2—2 of Figure 3, and

Figure 3 is a vertical section taken along the line 3—3 of Figure 2.

Referring more particularly to the drawing, 10 designates generally a housing having circular end walls 11 and 12 and a cylindrical wall 13. 5 The end walls 11 and 12 are removably connected to the cylindrical wall 13.

The cylindrical wall is provided with a pair of openings 14 and 15 through which the glued tape is adapted to pass and this tape is inserted beneath a guide member 16 having a central rib 17 for maintaining the two tapes in proper position.

Where two types of tape are employed one of the tapes is wound upon a spool 18, while the other tape is wound upon a spool 19. The inner 15 ends of the spools are in abutment, as shown at 20, and each spool is provided with a flange 21 or 22 as the case may be.

The spools are supported by an axle or pin 25 which has a head 26 abutting the end wall 12 20 while the head of a set screw 27 is threaded into a hollow end 28 of the pin whereby the axle or pin is secured to the end walls.

On the spool 18 may be placed a roll 29 of white tape while on the spool 19 is placed a roll 30 of 25 black tape.

Projecting from a housing 10 is a container 31 which has a chamber 32 to receive a moistener 33. This moistener may be of the usual type such as a sponge or felt which is saturated with a liquid. The outer end 34 of the moistener projects slightly beyond the open end 35 of the container 31.

One wall 36 of the chamber 32 is curved and a plate 37 which is also curved and concentric with 35 the wall 36 forms with the plate 37 a pair of guides for the tape 29. The outer ends of the guides, as shown at 38 and 39, terminate adjacent an edge of the opening 35 of the chamber 32.

A cover 40 is hinged at 41 on a wall which is 40 opposite the wall 36 and adjacent the outer edge of the wall which partially embraces the opening 35. This cover is curved and substantially closes the opening 35. Side flanges 42 engage the side walls 43 of the container 31. 45

It will be noted that the open end 35 of the container 31 is located substantially in a plane which is parallel to a tangent to the circular wall 13 of the housing 10. The wall which is opposite the curved wall 36 of the container is substantially in a plane likewise which is parallel to a tangent to the circular wall 13. 50

The tape normally projects through the openings 14 and 15 and is extended beneath the guide member 16 and sufficiently beyond the same so 55

that it may be grasped by the finger or engaged by the thumb of the operator and moved to be received by one of the guide members 38^a or 39^a as the case may be.

5 The tape is then threaded through one of the guide members 38^a or 39^a depending upon which tape is employed for the purpose and the cover 40 is opened and laid back so that it projects outwardly of the pivot 41 on the container 31. By 10 this position of the open cover 40 the tape will be provided with a rest over which the tape is drawn so that it will neatly be pressed against the projecting end 34 of the moistener 32.

I claim:

15 A target pasting device comprising a housing for storing a roll of tape and provided with an outlet through which the tape is threaded, the

housing having an offset portion providing a container for a tape moistener, the container having an open end, a moistener in the container and projecting outwardly of the open end thereof, a curved guide on a wall of the container and having an outlet adjacent an edge of the container so that the tape may be drawn directly over the projecting portion of the moistener and at approximately a right angle to the path of the tape through the guide, a hinged cover for the open 10 end of the container, swingable outwardly therefrom, and in line with the path of the moving tape for supporting the projecting portion of the tape in a plane which passes through the top of the moistener.

15 WILLIAM E. HUMMEL.
